UNITED STATES PATENT OFFICE.

ANDREW HOLMES, OF ATTLEBORO, MASSACHUSETTS, ASSIGNOR TO O. W. HAWKINS AND COMPANY, OF SAME PLACE.

DESIGN FOR A TONGUE FOR BELT-BUCKLES.

SPECIFICATION forming part of Design No. 34,264, dated March 26, 1901.

Application filed February 14, 1901. Serial No. 47,379. Term of patent 3½ years.

To all whom it may concern:

Be it known that I, ANDREW HOLMES, a resident of Attleboro, in the county of Bristol and State of Massachusetts, have invented and produced a certain new and useful Design for a Tongue for a Belt-Buckle; and I do hereby declare that the following is a full, clear, and exact description thereof, reference being had to the accompanying drawings, and to the letters of reference marked thereon, which form a part of this specification.

As shown in the drawings, the leading material feature of my design consists of a plate A, having one straight side a and its opposite side, at about one-third of its height from its lower end, made with a rounding projection b and extending to the top c in a curved tapering line, the lower side of said rounding projection b extending back in a slightly upwardly curving line e to the lower end f of the 25 plate, which, with the upper end c, is made square to the straight side a. A portion d of the plate on the straight side is turned down at a right angle to the plane of the body of the plate. (See Fig. 2.) Short straight projections g h extend out from the upper and lower end of the plate.

Having thus described my invention, I claim as new and desire to secure by Letters Patent—

The design for a tongue for a belt-buckle as herein shown and described.

In witness whereof I have hereunto set my hand, this 13th day of February, 1901, at Providence, in the county of Providence and 40 State of Rhode Island.

ANDREW HOLMES.

In presence of—

HOWARD E. BARLOW,
EDGAR S. MARSH.
